UNITED STATES PATENT OFFICE.

ALBERT E. NEWTON, OF LEOMINSTER, MASSACHUSETTS.

DESIGN FOR A BARRETTE.

No. 39,416.

Specification for Design.

Patented July 14, 1908.

Application filed April 4, 1908. Serial No. 425,284. Term of patent 3½ years.

To all whom it may concern:

Be it known that I, ALBERT E. NEWTON, a citizen of the United States, residing at Leominster, in the county of Worcester and Commonwealth of Massachusetts, have invented a new, original, and ornamental Design for Barrettes; and I do declare the following to be a full, clear, and exact specification of the same.

My invention relates to a design for bar-

rettes—which is illustrated in the accompanying drawings, in which the figure is an elevation of a barrette showing my new design.

I claim:

The ornamental design for a barrette, as shown.

ALBERT E. NEWTON.
